(57) **CLAIM**

What is claimed is the ornamental design for a laundry tub lint trap and overflow guard, as shown and described.

DESCRIPTION

FIG. 1 is a perspective view of a laundry tub lint trap and overflow guard, showing the new design;

FIG. 2 is a bottom plan view thereof;

FIG. 3 is a top plan view thereof;

FIG. 4 is a front elevational view thereof, the rear elevational view being a mirror image thereof; and,

FIG. 5 is a left-side elevational view thereof, the right-side elevational view being a mirror image thereof.
